UNITED STATES PATENT OFFICE.

MORRIS SHERAS, OF CHICAGO, ILLINOIS, ASSIGNOR TO A. D. JOSLIN MANUFACTURING CO., OF CHICAGO, ILLINOIS, A CORPORATION OF ILLINOIS.

HAND STAMP.

Application filed September 23, 1922. Serial No. 589,981.

To all whom it may concern:

Be it known that I, MORRIS SHERAS, a citizen of the United States, residing at Chicago, in the county of Cook and State of Illinois, have invented certain new and useful Improvements in Hand Stamps, of which the following is a specification.

This invention relates generally to printing devices and especially to such devices 10 of the sort commonly known as hand stamps. The particular kind of stamp to which the present invention especially relates is that wherein printing members are carried in a swinging head and adapted for cooperation 15 with a platen to form printed impressions upon a sheet, the printing members being adjustable so that the nature of the printing may be changed at selection.

The general object of the present invention 20 is to afford certain improvements in the construction of stamps of this character with the purpose of facilitating the proper setting of the printing members with rapidity and accuracy.

25 A further object is the provision of a structure for facilitating the setting of printing members in a stamp so that the indicators may be read in the proper sequence in which the character will appear in 30 the legend printed by the device.

A further object of the invention is the provision of apparatus in which the foregoing objects may be accomplished in a stamp which is arranged to print upon the upper 35 surface of a sheet disposed on the platen, so that the operator may properly place the desired portion of the sheet for reception of the printing.

40 A further object is the provision of an improved indicating device whereby the position of the ribbon with respect to the ribbon feeding spools or shafts is presented to the attention of the operator.

45 A further purpose of the invention is the accomplishment of the foregoing objects in a mechanism which is positive in operation and of simple, durable and sturdy construction so that it will have a prolonged term of serviceability.

50 Other and further objects of the invention will be pointed out hereinafter, indicated in the appended claims or obvious to one skilled in the art from the present disclosure.

55 For the purpose of the present applica-

tion I have elected to disclose one form in which the invention may be embodied, but it is to be understood that the same is here presented for illustrative purpose only and therefore that it is not to be accorded any 60 construction having the effect of limiting what I purport to secure, short of the true and most comprehensive scope of the invention in the art.

In the accompanying drawing forming a 65 part of this specification,

Fig. 1 is a front elevation of a stamp embodying my invention;

Fig. 2 is a section on substantially line 70 2-2 of Fig. 1;

Fig. 3 is a sectional elevation on substantially line 3-3 of Fig. 2;

Fig. 4 is a cross-section substantially on line 4-4 of Fig. 3;

Fig. 5 is a detail in the nature of a section 75 substantially on line 5-5 of Fig. 1;

Fig. 6 is a detail in the nature of a bottom view of the structure illustrated in Fig. 5.

Described generally, the present invention involves the employment of an oscillatory 80 frame member upon which are mounted adjustable type carrying members associated in such fashion that selected type may be collated at the printing line by adjustment of certain indicating members arranged ex-

teriorly of the housing in which the type members are mounted. Associated with the type-carrying members is suitable ribbon feed mechanism whereby an inked ribbon may be fed across the type presented at the 85 printing line in such relationship that when the swinging frame is moved to impact a suitably supported platen, the type will print upon a sheet supported thereon, through the medium of the ribbon. Stamps 90

of this type are employed generally in railway ticket offices, banking houses and other establishments where it is necessary to set the type to print different figures or legends, not only from day to day, but also frequently during a day incident to the sale of 95 tickets. It is important that this setting be accomplished with speed and with accuracy,

whence arises the desirability that the indicators for the setting means, whereby the 100 position of the type is determined, be arranged to read in the normal order in which characters will be printed. One feature of the present invention is directed particularly to the obtaining of that result, and the 105

110

nature of the construction will be best understood by reference to the drawing in detail. In the drawings it will be understood that the numeral 1 designates a base member 5 upon which a swinging frame member is pivotally mounted on a pintle 2, said frame carrying at its free end a housing 4. A spring 5 normally holds the housing lifted in a position above a platen 6 which is 10 carried on the base member 1. The housing is closed at the sides by side plates 7 which carry at their lower margins a type plate 8 upon which may be formed the permanent type characters which the stamp is designed 15 to print. This type plate is slotted to accommodate the movable type characters, the arrangement of which will now be explained. In the left hand side plate 7 is journaled a sleeve 9 through which extends 20 a substantial shaft 10 and to which shaft the sleeve is connected for rotation, as by the pin 11. Keyed to the sleeve 9 is a type wheel 12 which has joined thereto the detent wheel 14 having a toothed or 25 serrated margin, said detent wheel being of less diameter than the type wheel. A detent guide disk 15 is joined to the detent wheel 14 on the side opposite the type wheel 12. The type wheel carries 30 peripherally arranged type characters 16 which are arranged to be presented at the printing line in the slot of the type plate 8. At the end of the sleeve 9, on the shaft 10, is arranged a collar 17 35 which at its other end abuts the end of a sleeve 18 rotatably mounted on the shaft 10. The sleeve 18 in turn carries a rotatable collar 19 which is journaled in the right hand side frame 7 and which carries at its 40 inner end, adjacent the side plate, a spur gear 20. Rotatably mounted upon the sleeve 18 is a type wheel 21 having a detent wheel 22 and guide disk 24 fixed thereto. Keyed to the sleeve 18 is a type wheel 45 25 having the conjoined detent wheel 26. Between the type wheel 25 and the type wheel 12 a type wheel 27 with its conjoined detent wheel 28 are rotatably mounted on the collar 17. 50 Journalled in the right hand side plate 7 and a bracket 29 depending from the top of the housing 4 is a shaft 30 carrying at its right hand end a spur pinion 31 which meshes with the pinion 20, and at its left hand end a setting gear 32 which meshes with the detent wheel 28 of the type wheel 27. Mounted on the housing behind the shaft 10 are the restraining detents 34 which are pressed by springs 35 into engagement with the detent wheels 14, 28, 26 and 22, the function of said detents being to restrain the type wheels with their type in proper alignment at the printing line. On the left hand end of the shaft 10 an indicator wheel 36 65 is mounted exteriorly of the casing, which

indicator wheel bears legends corresponding to those carried on the type wheel 12. On the projecting end of the sleeve 19 an indicator wheel 37 is mounted exteriorly of the casing, which indicator wheel bears on 70 its periphery characters corresponding to those carried on the type wheel 27, and the right hand end of the sleeve 18 carries an indicator wheel 38 having on its periphery characters corresponding to the type 75 characters on the type wheel 25. These respective indicator wheels are fixed to the respective members upon which they are mounted so that the latter may be rotated by manipulation of the indicator wheels as 80 desired. Mounted on the exterior of the side plates 7 are guides 39 which are associated with the indicator wheels in such fashion as to designate the characters thereon corresponding to those of the type wheels 85 presented at the printing line.

In the operation of the mechanism thus far described, adjustment of the type wheel 12, which I will designate the month wheel, is accomplished by rotation of the indicator wheel 36, movement being transmitted therefrom to the month wheel through the instrumentality of shaft 10 and sleeve 9. Adjustment of the type wheel 27, which I will designate the tens wheel, is accomplished by manipulation of the indicator wheel 37, movement being transmitted therefrom through sleeve 19 and gears 20, 31 and 32 to the detent wheel 28. Adjustment of the type wheel 25, which I will designate the units wheel, is accomplished by manipulation of the indicator wheel 38, the movement being transmitted therefrom through the sleeve 18. Hence it will be obvious that a desired legend may be set 105 up on the printing line by manipulation of the indicator wheels, upon which indicator wheels the legends may be read in the normal relationship in which they are associated on the printing line. Adjustment of the type wheel 21, which I will call the year type wheel, is accomplished by manipulation of that wheel directly, at the place where it is exposed on the printing line through the slot in the type plate 8. 115 In the ordinary use of a device of this character, particularly where it is employed as a dating stamp, it will be obvious that adjustment of the year wheel will be required only at intervals of approximately a year, 120 whereas adjustment of the month and day printing type may be required at much more frequent intervals. The above described mechanism affords means whereby these adjustments may be made quickly and 125 with accuracy and, due to the fact that the characters are shown on the indicators in their normal order, the possibility of improper setting is largely obviated.

It will be understood that the inked rib- 130

bon 40 is guided in the casing 4 so as to extend across the type provided on the type plate 8 and on the type wheels at the printing line. This ribbon is connected 5 at its ends to the ribbon reels 41 and 42 which are journaled in the side plates 7. Suitable actuating means, which may be of the sort disclosed in my copending application Serial No. 451,512, filed March 11, 1921 10 is carried in the casing 4 for actuating the ribbon reels to wind the ribbon off of one and onto the other. Said actuating means includes a pivoted link 44 connected to the base member 1, through which movement is 15 transmitted to the reel actuating mechanism upon oscillation of the swinging frame member. To permit the rapid reeling of the ribbon, the right hand ends of the reels are provided with spur pinions 50 which 20 lie adjacent the right hand cover plate 7. Journaled on this cover plate in meshing cooperation with the pinions 50 are the reeling pinions 51 which are so disposed that portions of their peripheries extend through 25 slots in the casing 4 so as to be manually engageable exteriorly thereof. By rotation of the proper reeling pinion 51 the reels may be rotated to wind the ribbon onto either one.

30 Inasmuch as the feed of the ribbon is accomplished automatically incident to operation of the stamp, means are provided for reversing the direction of feed of the ribbon when desired. This means includes 35 a manually adjustable knob 52. It is important that the direction of feed of the ribbon be reversed before it is exhausted from a reel or before its connecting means are brought to a position where they underlie the printing plate 8. In order to insure the attention of the operator being directed to the necessity for reversing the ribbon I have provided a novel indicating device so arranged as to be at all times directly in the vision and under the attention of a person operating the stamp. This indicating device includes a plate 54 which is mounted on the upper front portion of 45 the housing 4 in covering relationship to an aperture through that wall of the housing. This plate carries a boss 55 extending through the aperture in the housing, in which boss is journaled a shaft 56 carrying a pointer 57 arranged to travel across 50 the outer surface of the plate 54. Upon the inner end of the shaft 56 is mounted a small spur pinion 58 which meshes with a larger pinion 59 journaled on a stud 60 which is seated in the boss 55. Conjoined 55 to the pinion 59 is a crank 61 extending radially of the pinion 59 and carrying a member 62 arranged for operative association with the ribbon reel 41. A spring 64 is mounted on the stud 60 and exerts its 60 pressure against the member 62 to urge it

toward the ribbon reel. As the ribbon is wound upon the reel, the increasing thickness thereof swings the member 62 away from the reel, thereby actuating the pinion 59 through the instrumentality of the crank 70 61, and rotating the pinion 58, so that the pointer 57 will be caused to travel across the face of the plate 54. The latter is provided with suitable indicating means 65 associated with the pointed 58 for marking the limits at which the direction of feed of the ribbon should be reversed. This construction permits the disposal of the indicating pointer where it will be observed by the operator every time the stamp is used, 80 by virtue of which fact the likelihood of the ribbon being wound entirely off of either reel is obviated to a large extent.

85 From the foregoing it will be observed that my invention effects material improvement in devices of this character by eliminating possibilities of error in the setting of the type wheels, as well as by facilitating the adjustment thereof, and that it also simplifies the mounting of ribbons in the 90 machine and affords protection for the ribbon and the type by giving quite obvious indicated as to when the direction of feed of the ribbon should be reversed. Due to the simplicity of the construction and to 95 the strong support afforded the type wheels by the shaft 10 and the sleeves carried thereon, the device is extremely durable and will retain its accuracy through a long period of the trying usage of which such devices 100 customarily are subjected.

100 I claim:

1. In a stamp, a combination comprising a movable housing, type carriers adjustably mounted therein in alignment, said type carriers comprising a middle type carrier together with a left type carrier to the left side thereof and a right type carrier to the right side thereof, adjustable indicator 105 wheels mounted on the exterior of the housing in alignment, said indicator wheels comprising a middle indicator together with a left indicator to the left side thereof and a right indicator to the right side thereof, operable connections joining the middle, left and right indicators respectively with the middle, left and right type carriers, whereby the type carriers may be adjusted by operation of the indicators, and the indicators being provided with legible characters corresponding to the type on their conjoined 110 type carriers.
2. In a stamp, in combination, a housing, adjustable type wheels co-axially mounted therein, an intermediate type wheel adjustably mounted between said first mentioned type wheels and co-axial therewith, operable indicators disposed externally of the housing and operably connected respectively to the first mentioned type wheels, and an in- 115 120 125 130

4
termediate indicator disposed between said first mentioned indicators and operably connected to the intermediate type wheel, said indicators being adjustable to adjust the type 5 wheels and carrying legible characters corresponding to the type carried on their associated type wheels.

3. In a stamp, in combination, a housing, co-axially arranged type wheels adjustably 10 mounted therein, an intermediate type wheel disposed between said type wheels and arranged co-axially therewith, an indicator on one side of the housing operably connected to the adjacent type wheel, an indicator on 15 the other side of the casing operably connected to another type wheel, a third indicator associated with the second indicator and between the same and the casing, means operably connecting said third indicator 20 with the intermediate type wheel, said indicators being operable to adjust the type wheels and bearing legible characters readable in association and corresponding to 25 type characters on the respective type wheels.

4. In a stamp, in combination, a housing, a shaft extending through the same, a type wheel operably connected therewith, an indicator whereby the shaft may be rotated 30 and bearing legible characters corresponding to the type on said type wheel, a sleeve rotatably mounted on the shaft, a second type wheel mounted on said sleeve, an indicator connected to said sleeve externally of the 35 housing and bearing characters corresponding to the type on said second type wheel,

an intermediate type wheel mounted on the shaft between the aforementioned type wheels, a collar rotatably mounted on the sleeve, an indicator connected to said sleeve externally of the casing and bearing legible characters corresponding to the type on the intermediate type wheel, a setting shaft 40 mounted in the housing, and gearing connecting said collar with the intermediate 45 type wheel.

5. In a stamp, in combination, a housing, a plurality of type carriers arranged in alignment transversely therein, a plurality of indicators operably connected with the type 50 carriers and arranged in alignment transversely of the housing and externally thereof, ribbon reeling means within the housing for feeding a ribbon across portions of the type wheels, an indicator mounted on the 55 front of the housing, and means operable by ribbon on the reeling means for moving said indicator to indicate the position of the ribbon.

6. In a stamp, in combination, a housing, 60 type wheels disposed on axes transversely of the housing, ribbon reels arranged on axes extending transversely of the housing, an indicator mounted on the front of the housing and movable on an axis extending 65 transversely of the ribbon reels, and means operable by ribbon on the reels for moving said indicator about its axis to designate the position of the ribbon.

In testimony whereof I have hereunto sub- 70 scribed my name.

MORRIS SHERAS.
